[57] CLAIM

The ornamental design for a seat, as shown and described.

DESCRIPTION

FIG. 1 is a left top perspective view of the chair embodiment of the seat of the present invention;

FIG. 2 is a right side view of the chair of FIG. 1, the left side being a mirror image;

FIG. 3 is a front view of the chair of FIG. 1;

FIG. 4 is a rear view of the chair of FIG. 1;

FIG. 5 is a top view of the chair of FIG. 1;

FIG. 6 is a bottom view of the chair of FIG. 1;

FIG. 7 is an enlarged fragmentary view taken along the lines 7-7 of FIG. 3 in the direction of the appended arrows;

FIG. 8 is a left top perspective view of the settee embodiment of the seat of the present invention;

FIG. 9 is a right side view of the settee of FIG. 8, the left side being a mirror image;

FIG. 10 is a front view of the settee of FIG. 8;

FIG. 11 is a rear view of the settee of FIG. 8;

FIG. 12 is a top view of the settee of FIG. 8;

FIG. 13 is a bottom view of the settee of FIG. 8;

FIG. 14 is a front perspective view of an alternative chair embodiment of the seat of the present invention;

FIG. 15 is a right side view of the chair of FIG. 14, the left side being a mirror image;

FIG. 16 is a front view of the chair of FIG. 14;

FIG. 17 is a back view of the chair of FIG. 14;

FIG. 18 is a top view of the chair of FIG. 14; and,

FIG. 19 is a bottom view of the chair of FIG. 14.
